JOURNAL ARRANGEMENT

Robert B. Cottrell, Chicago, Ill., assignor to
American Steel Foundries, Chicago, Ill., a corporation of New Jersey

Application June 28, 1944, Serial No. 542,543

11 Claims. (CL 105—223)

1

My invention relates to railway car trucks and more particularly to a novel axle box or journal box mounting especially adapted to afford relative limited angling between the box and the truck frame in every direction as may be required in actual service, wherein the wheel and axle assemblies move relative to the frame due to various track conditions.

My invention is particularly adapted to journal boxes of the roller bearing type; however, if desired, the invention may be utilized for other types of journal boxes.

A specific object of my invention is to design a railway car truck wherein the side frame is provided with a spherical surface seated upon a complementary spherical surface atop the journal box, the side frame and journal box being afforded novel means for limiting relative angularity between the box and the frame.

Another object of my invention is to provide in a journal box mounting such as above described, a novel tie bar or securing bracket underlying the box and secured to the frame, said bracket having a spherical surface slightly spaced from an adjacent spherical surface of the journal box to accommodate the above-mentioned angularity between the box and the frame. The bracket and the box are also provided with complementary abutment faces for limiting vertical angling.

In the drawings,

Figure 1 is a sectional view through a side frame and journal box embodying my invention, said view being taken approximately in the transverse vertical plane indicated by the line 1—1 of Figure 2.

Figure 2 is a fragmentary side elevation of my novel side frame construction with the journal box removed from its associated opening.

Figure 3 is a plan view of the side frame securing bracket shown in Figure 2 and illustrating the connection of said bracket to the side frame.

Figure 4 is a sectional view taken in the horizontal plane indicated by the line 4—4 of Figure 1.

Figures 5 and 6 illustrate a modification of my invention, Figure 5 being a fragmentary sectional view comparable to Figure 1 and taken in the vertical plane indicated by the line 5—5 of Figure 6. Figure 6 is a fragmentary side elevation of the side frame shown in Figure 5 with the journal box removed therefrom.

Describing my invention in detail and referring first to the embodiment thereof illustrated in Figures 1 to 4 inclusive, the side frame comprises the diagonal tension and compression members 2 and 4 defining the window opening 3 and

2

merging at their ends in a box section above the pedestal or journal box opening 10 defined by the side frame and the removable bracket or tie bar 12.

5 The side frame above the opening 10, as best seen in Figure 1, is of box section comprising the top and bottom webs 14 and 16 and the inboard and outboard walls 18 and 20, the top wall 14 being cored away at 22 (Figure 2) to afford an opening for the application and removal of the nut 24 threaded on the securing bolt 26 which extends through aligned bosses 28 and 30 formed respectively on the bracket 12 and on the side frame between the inboard and outboard walls 18 and 20. A nut 32 is also threaded on the lower end of the bolt 26. The bracket 12 is also secured to the side frame by another bolt 34 which extends through aligned bosses 36 and 38 formed respectively on the bracket 12 and side frame gusset 40. Nuts 42 and 44 are threaded on opposite ends of the bolt 34.

10 The bottom wall 16 is formed on the bottom thereof with a spherical surface 46 struck on radius A (Figure 1) from the center of curvature B, said surface 46 being defined by the outboard and inboard converging abutment surfaces 48 and 50 adapted for abutment respectively with the outboard and inboard surfaces 52 and 54 of the journal box generally designated 56, said surfaces 52 and 54 defining the outboard and inboard edges of a spherical surface 57 on the top of the journal box complementary to the before-mentioned spherical surface 46 and affording a seat therefor.

15 It may be noted that the surface 48 and the adjacent surface 52 are disposed in planes C and D converging at a point on a circle E, struck from the point B. By means of this construction, the planes C and D are both intersecting at a common point on a radius of the circle E, thus insuring flat face contact between the surfaces 48 and 52 to limit relative vertical angling of the side frame and journal box, as will be clearly apparent to those skilled in the art. It 20 will also be understood that the surfaces 50 and 54 are similarly disposed in converging planes intersecting at a common point on the circle E.

25 It may be noted at this point that the tie bar 12 comprises a spherical surface 58 struck from the radius F, said surface being concentric with and slightly spaced from a complementary spherical surface 60 formed on the bottom of the journal box 56, thus accommodating the above-mentioned angling between the side frame 30 and the box.

The surface 60 is defined at its inboard and outboard margins by the diagonal converging faces 62 and 64 formed and arranged for cooperation with inboard and outboard diagonal converging faces 66 and 68 formed on the tie bar 12, and it will be understood that the surface 62 and the adjacent face 66 are formed respectively in converging planes G and H intersecting at a common point on the circle E, thus affording flat face contact therebetween simultaneously with the contact between the surfaces 48 and 52 to limit vertical angling between the box and the frame in one direction. Similarly, the surface 64 and the adjacent face 68 are disposed in planes intersecting at a common point on the circle E, whereby they are afforded flat face engagement therebetween simultaneously with the engagement between the surfaces 50 and 54 to limit vertical angling between the box and the frame in the other direction.

The outboard wall 20 is formed with a hollow lug 10 received within a bracket 72, U-shaped in horizontal cross-section with the parallel walls of said bracket having the inner surfaces thereof converging toward the lug 10, as seen in Figure 4, and it will be understood that the parallel surfaces on the lug 10 have flat face engagement with the converging surfaces of the bracket 72 to limit horizontal angling between the side frame and journal box in opposite directions. The axle 14 of the wheel and axle assembly fragmentarily indicated at 76 is received within the journal box 58 and is mounted therewithin by means of inboard and outboard roller bearing units, the inboard bearing unit consisting of an outer race 78 fitted within the box against a shoulder 80 therein, and an inner race 82 carried by the axle 14. Roller bearings 84, 84 are disposed between the races 78 and 82. The outboard roller bearing unit comprises an outer race 86 fitted within the journal box against a shoulder 88 therein and an inner race 90 sleeved on the axle 14, roller bearings 92, 92 being disposed between the inner and outer races 90 and 86. A sleeve 94 is disposed between the races 82 and 90 for maintaining the same in proper spaced relationship, and a retaining collar 96 is press fitted on the outboard end of the axle for positioning the races 90 and 82 and the sleeve 94.

A cover plate 98 is secured as at 100, 100 to the outboard face of the journal box, and an inboard cover plate 102 is secured as at 104, 104 to the inboard side of the box, said plate 102 being grooved at 106, 106 and defining with the shrink collar 108 a labyrinthine passage 110 to prevent the escape of oil from within the journal box.

Referring now to the modification of my invention illustrated in Figures 5 and 6, the side frame comprises the diagonal tension and compression members 202 and 204 defining the window opening 206 and merging at their ends in a box-section portion best illustrated in Figure 5, which shows the top and bottom webs 208 and 210 of the side frame, as well as the inboard and outboard walls 212 and 214 thereof, said bottom wall being formed with a spherical surface 216 as in the previously described embodiment.

The journal box is provided on the top thereof with a spherical surface 218 (Figure 5) affording a seat for the before-mentioned surface 216 which is defined at its inboard and outboard edges by the converging abutment surfaces 220 and 222 for cooperation respectively with complementary abutment surfaces 224 and 226 of the journal box, as in the previously described em-

bodiment, said journal box receiving the journal end of the wheel and axle assembly 228 which is suitably mounted therein, as in the previous embodiment, by roller bearing units generally designated 230, 230.

The outboard wall 214 is provided with a lug 232 having an opening 234 therethrough for the reception of a bolt 236 carried by an upstanding lug 238 on the journal box 240 at each side of the lug 232. The top and bottom margins of the opening 234, as best seen in Figure 6, are arcuately formed to accommodate limited vertical angling of the side frame longitudinally thereof, and said opening is somewhat triangular in vertical cross-section, as best seen in Figure 5, to accommodate relative vertical angling between the wheel and axle assembly 228 and the side frame transversely thereof, as best seen in Figure 5.

It will be understood that the arrangement illustrated in Figures 5 and 6 is substantially identical to the previously described embodiment, except for the elimination of the tie bar and for the particular connection between the side frame and journal box afforded by the bolt 236 and the lug 232, as above described; and it may be noted that because of the elimination of the tie bar, the side frame is provided beneath the spherical surface 218 with the spaced depending pedestal lugs or jaws 242, 242 adapted to embrace the journal box therebetween to prevent accidental disassembly thereof with respect to the side frame.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a side frame comprising a journal box opening partly defined by a removable tie bar secured to said frame, a wheel and axle assembly comprising a journal box received within said opening and having a surface around the axis of said assembly formed as a segment of a sphere, said surface affording a seat for a complementary surface of said frame, said tie bar having a spherical surface slightly spaced from but concentric with said first-mentioned surface, abutment surfaces on the outboard side of said frame and adjacent portion of said box respectively, formed and arranged for flat face engagement simultaneously with the engagement of similar surfaces on the inboard side of said bar and the adjacent portion of said box, abutment surfaces on the inboard side of said frame and the adjacent portion of said box respectively, formed and arranged for flat face engagement simultaneously with the engagement of similar surfaces on the outboard side of said bar and the adjacent portion of said box to limit relative vertical angling between the side frame and journal box, and means loosely interlocking said box and said frame, said means comprising a lug on the outboard side of said frame received within and spaced from a U-section bracket atop said box, said bracket having converging surfaces on the walls thereof on opposite sides of said lug for flat face engagement with the adjacent surfaces of said lug to limit relative horizontal angling between said

frame and box in opposite directions on said spherical surfaces.

2. In a railway car truck, a wheel and axle assembly, a journal box mounted thereon and comprising a spherical top surface defined at its inboard and outboard edges with diagonal converging abutment surfaces, a side frame comprising a complementary spherical surface seated on said first-mentioned surface and defined by inboard and outboard converging abutment faces, each of said abutment surfaces and the adjacent abutment face lying in respective planes intersecting at a common point on an arc struck from the center of curvature of said spherical surfaces, and a securing bracket removably connected to said frame and underlying said box, said bracket and said box presenting slightly spaced spherical surfaces struck from said center of curvature, each of said last-mentioned surfaces being defined at its inboard and outboard edges by converging plane abutment faces, the face on each side of said bracket being formed and arranged for engagement with the adjacent face on said box simultaneously with the engagement of one side frame abutment surface with the adjacent abutment face for limiting relative vertical angling between said frame and said box, and a lug on the outboard side of said frame received within and spaced from a U-section bracket atop said box, said bracket having converging surfaces on the walls thereof on opposite sides of said lug for flat face engagement with the adjacent surfaces of said lug to limit relative horizontal angling between said frame and box in opposite directions on said spherical surfaces.

3. In a railway car truck, a wheel and axle assembly, a journal box carried thereby and comprising a spherical top surface defined at its inboard and outboard edges by plane diagonal converging abutment surfaces, a side frame comprising a complementary spherical surface seated on said first-mentioned surface and defined by inboard and outboard plane converging abutment faces, each of said abutment surfaces and the adjacent abutment face being adapted for flat face engagement to limit relative vertical angling between the side frame and journal box and being disposed in respective planes intersecting at a common point on an arc struck from the center of curvature of said spherical surfaces, and a lug on said frame received within and spaced from a U-section bracket on the top of said box, said lug being afforded limited movement within said bracket and being engageable therewith for limiting relative horizontal movement between the side frame and the box on said spherical surfaces.

4. In a railway car truck, a side frame member comprising an opening partly defined by a removable tie bar secured to said frame member, a wheel and axle assembly comprising a journal box member received within said opening and having a surface around the axis of said assembly formed as a segment of a sphere, said surface affording a seat for a complementary surface of said frame member, said tie bar having a spherical surface slightly spaced from but concentric with said first-mentioned surface, abutment surfaces on the outboard side of said frame member and the adjacent portion of said box member respectively formed and arranged for engagement simultaneously with the engagement of similar surfaces on the inboard side of said bar and the adjacent portion of said box mem-

ber, abutment surfaces on the inboard side of said frame member and the adjacent portion of said box member respectively, formed and arranged for engagement simultaneously with the engagement of similar surfaces on the outboard side of said box and the adjacent portion of said box member to limit relative vertical angling between said members, and means loosely interlocking said members, said means comprising a lug on one of said members outboard said frame member received within and spaced from a U-section bracket on the other member, said bracket having converging surfaces on the walls thereof on opposite sides of said lug for flat face engagement with the adjacent surfaces of said lug to limit relative horizontal angling between said members in opposite directions on said spherical surfaces.

5. In a railway car truck, a wheel and axle assembly, a journal box member carried thereby and comprising a spherical top surface defined at its inboard and outboard edges by plane diagonal abutment surfaces, a side frame member comprising a complementary spherical surface seated on said first-mentioned surface and defined by inboard and outboard plane converging abutment faces, each of said abutment surfaces and the adjacent abutment face being adapted for engagement to limit relative vertical angling between said members and being disposed in respective planes intersecting at a common point on an arc struck from the center of curvature of said spherical surface, and a lug on one of said members received within and spaced from a U-section bracket on the other member, said lug being afforded limited movement within said bracket and being engageable therewith for limiting relative horizontal movement between said members on said spherical surfaces.

6. In a railway car truck, a wheel and axle assembly including a journal box member with a spherical surface atop thereof, a side frame member with a complementary surface seated on said first-mentioned surface, and means limiting relative movement between said members, said means including a lug on one of said members received within and spaced from a bracket on the other member, said bracket having surfaces converging toward surfaces on said lug for flat face engagement therewith to limit relative horizontal angling therebetween on said spherical surfaces said lug and bracket being disposed exteriorly of respective members at points remote from said surfaces.

7. In a railway car truck, a wheel and axle assembly including a journal box, a roller bearing unit therein, and an axle mounted in said unit, a side frame comprising a spherical surface seated on a complementary spherical surface atop said box, said surfaces affording relative angling in every direction between said box and said frame, complementary diagonal abutment surfaces on said box and said frame defining the inboard and outboard margins of said spherical surfaces and adapted to limit vertical angling between the box and frame, and a lug on said frame projecting laterally therefrom and received within a bracket atop said box for loosely interlocking said frame therewith, said bracket having the portions thereof on opposite sides of said lug provided with surfaces converging toward said lug for flat face engagement therewith to limit relative horizontal angling of said box and said frame.

8. In a railway car truck, a side frame com-

prising a journal box opening partly defined by a removable tie bar secured to said frame, a journal box received within said opening and having a surface therearound defined as a segment of a sphere, said surface affording a seat for a complementary spherical surface of said frame, said tie bar having a spherical surface slightly spaced from, but concentric with said first-mentioned surface, and means on said box and frame for limiting relative angling therebetween, said means comprising spaced walls atop said box receiving therebetween a projection on one side of said frame in spaced relation thereto and engageable therewith to limit relative horizontal angling between said frame and box.

9. In a railway car truck, a side frame comprising a journal box opening partly defined by a removable tie bar secured to said frame, a journal box received within said opening and having a surface therearound defined as a segment of a sphere, said surface affording a seat for a complementary spherical surface of said frame, said tie bar having a spherical surface slightly spaced from, but concentric with said first-mentioned surface, and means on said box and frame for limiting relative angling therebetween, said means comprising a lug on said frame projecting laterally therefrom in a horizontal plane above said surfaces received within a U-shaped bracket atop said box, said lug being spaced from the portions of said bracket on opposite sides thereof and having engagement therewith to limit relative horizontal angling of said box and said frame on said spherical surfaces.

10. In a railway car truck, a wheel and axle assembly including a journal box with a spherical surface atop thereof, a side frame with a com-

plementary surface seated on said first-mentioned surface, and means limiting relative movement between the box and frame, said means including a lug on the outboard side of said frame loosely received within a bracket atop said box and adapted to have flat face engagement therewith for limiting relative horizontal angling between said box and said frame on said spherical surfaces.

11. In a railway car truck, a wheel and axle assembly including a journal box member with a spherical surface atop thereof, a side frame member with a complementary surface seated on said first-mentioned surface, and means limiting relative movement between said members, said means including a vertical projection on one of said members received between and spaced from vertical walls on the other member, said walls having engagement with said projection to limit relative horizontal angling of said members on said spherical surfaces, said projections and walls extending exteriorly of said members in a horizontal plane above said surfaces.
